[57] CLAIM

The ornamental design for a retro-reflective element for
bicycle wheel spokes or similar article, as shown and
described.

DESCRIPTION

FIG. 1 is a top perspective view of a retro-reflector
element for bicycle wheel spokes or similar articles
showing my new design;

FIG. 2 is a bottom perspective view thereof;

FIG. 3 is an end elevational view thereof;

FIG. 4 is a top plan view thereof;

FIG. 5 is a right side elevational view thereof;

FIG. 6 is a bottom plan view thereof.
